UNITED STATES PATENT OFFICE.

OSCAR KROEHLE, OF LAKEWOOD, OHIO.

DESIGN FOR THE FRONT OF A SIGNAL-LENS.

58,916.

Specification for Design.

Patented Sept. 6, 1921.

Application filed January 17, 1921. Serial No. 438,010. Term of patent 14 years.

To all whom it may concern:

Be it known that I, OSCAR KROEHLE, a citizen of the United States, residing at Lakewood, in the county of Cuyahoga and State of Ohio, have invented a new, original, and ornamental Design for the Front of a Signal-Lens, of which the following is a specification, reference being had to the accompanying drawing, forming part thereof.

Said design comprises spaced light-transmitting portions adapted to display a substantially red color and having the configuration and relative arrangement required to form the sign "Stop," and also comprises a light-transmitting portion adapted to dis-

play a substantially red color and extending circumferentially of and spaced from said sign, and furthermore comprises portions extending between and contrasting with the aforesaid light-transmitting portions and having substantial opacity and preferably appearing black or dark in relation to said light-transmitting portions.

The drawing is a view of the front of a signal-lens, showing my new design.

I claim:

The ornamental design, substantially as shown, for the front of a signal-lens.

OSCAR KROEHLE.
